UNITED STATES PATENT OFFICE.

FERDINAND W. ZENKE, OF MERIDEN, CONNECTICUT.

SHOE-CLEANER.

No. 919,111.

Specification of Letters Patent. Patented April 20, 1909.

Application filed July 10, 1908. Serial No. 442,928.

To all whom it may concern:

Be it known that I, FERDINAND W. ZENKE, a citizen of the United States, residing at Meriden, in the county of New Haven, State 5 of Connecticut, have invented certain new and useful Improvements in Shoe-Cleaners; and I do hereby declare the following to be a full, clear, and exact description of the invention, such as will enable others skilled in 10 the art to which it appertains to make and use the same.

This invention relates to shoe and boot cleaning devices and has for one of its objects to simplify and improve the construction and increase the efficiency and utility of devices of this character.

Another object of the invention is to provide a simply constructed device of this character which may be readily cleaned and 20 worn or impaired parts renewed without discarding the other parts.

With these and other objects in view the invention consists in a base portion, a receptacle bearing upon the base and with an 25 encompassing seat in the upper rim, a frame detachably supported upon said seat and comprising spaced side members having brushes with the bristles extending inwardly therefrom and spaced transverse members 30 having brushes with the bristles extending upwardly therefrom, and rollers mounted for rotation upon the receptacle and extending between the transverse members and their brushes.

35 The invention further consists in certain novel features of construction as hereafter shown and described and then specifically pointed out in the claims, and in the drawings illustrating the preferred embodiment 40 of the invention, Figure 1 is a plan view of the improved device. Fig. 2 is a longitudinal section on the line 2—2 of Fig. 1. Fig. 3 is a transverse section on the line 3—3 of Fig. 2.

45 The improved device comprises a base or platform 10 which may be of any size or of any required material. Bearing upon the base 10 is a receptacle 11 hingedly connected to the base at 12 and with an encompassing 50 seat 13 in the upper edge. Bearing upon the seat 13 is a frame comprising spaced side members 14—15 and spaced transverse

members 16, the side members having inwardly extending brushes 17—18 and the transverse members having upwardly extending brushes 19, as shown. Mounted for rotation upon the side members of the receptacle 11 are rollers 20, one of the rollers extending transversely of the frame between each pair of the members 16, and so arranged 55 that the upper sides of the rollers project above the members 16. Rising from the seat 13 are half bearings 21 to receive the journals 22 of the rollers, and the lower faces of the side members 14—15 of the frame are provided with cavities to fit over the half bearings and likewise over the journals of the rollers, and thus retain the rollers in position. 60

The foot containing the shoe to be cleaned 70 is thrust between the brushes 17—18 and upon the rollers 20, and moved back and forth, the rollers supporting the foot, and preventing it from crushing the bottom brushes 19, as it otherwise would. The 75 dust and dirt detached from the shoes falls into the receptacle below the rollers and may be removed therefrom at any time by simply turning the receptacle together with the frame carrying the brushes upwardly 80 and removing the accumulated material.

The frame with its brushes is detachable from the lower receptacle, to enable the brushes to be cleaned from accumulated material. 85

The parts being easily separable, broken or impaired portions may be readily renewed without discarding the remaining portions of the device.

The parts may be constructed from any 90 required material, of or any required size.

What is claimed, is:—

1. A device of the class described comprising a receptacle having an encompassing seat in its upper rim, two side brushes engaging 95 in the seats at the sides of the receptacle with their bristles directed inwardly, a plurality of transverse brushes spaced apart and connecting said side brushes with their bristles directed upwardly, and rollers mounted for rotation upon said receptacle and extending between said transverse brushes. 100

2. A device of the class described comprising a receptacle, two side brushes supported

upon said receptacle with their bristles directed inwardly, a plurality of transverse brushes spaced apart and connecting said side brushes with their bristles directed upwardly, and rollers mounted for rotation upon said receptacle and extending between said transverse brushes.

In testimony whereof, I affix my signature, in presence of two witnesses.

FERDINAND W. ZENKE.
